US00D898028S

(12) **United States Design Patent** (10) **Patent No.:** **US D898,028 S**
Kang (45) **Date of Patent:** **** Oct. 6, 2020**

(54) **KEYBOARD FOR ELECTRONIC COMPUTERS**

(71) Applicant: **Toshiba Client Solutions CO., LTD.,**
 Tokyo (JP)

(72) Inventor: **ChingTing Kang**, Tokyo (JP)

(73) Assignee: **Toshiba Client Solutions CO., LTD.,**
 Tokyo (JP)

(**) Term: **15 Years**

(21) Appl. No.: **29/663,947**

(22) Filed: **Sep. 20, 2018**

(30) **Foreign Application Priority Data**

Jul. 6, 2018 (JP) 2018-014950

(51) **LOC (12) Cl.** **14-02**

(52) **U.S. Cl.**

USPC **D14/391**

(58) **Field of Classification Search**

USPC D14/203.4, 203.6, 247, 345-346,
 D14/315-327, 391-399, 455-457, 477,
 D14/507, 509; D18/1-2, 4.1-4.6, 7, 11;

(57) **CLAIM**

The ornamental design for a keyboard for electronic computers, as shown and described.

DESCRIPTION

FIG. 1 is a perspective view of a keyboard for electronic computers showing my new design,

FIG. 2 is a front elevational view thereof,

FIG. 3 is a rear elevational view thereof,

FIG. 4 is a top plan view thereof,

FIG. 5 is a bottom plan view thereof; and,

FIG. 6 is a right side elevational view thereof.

1 Claim, 4 Drawing Sheets
